CHARLES A. BUTCHER, OF EAST PITTSBURGH, PENNSYLVANIA, ASSIGNOR TO WESTINGHOUSE ELECTRIC & MANUFACTURING COMPANY, A CORPORATION OF PENNSYLVANIA.

AUTOMATIC RECLOSED CIRCUIT INTERRUPTER.

Application filed April 25, 1921. Serial No. 464,268.

My invention relates to circuit interrupters and particularly to automatic circuit interrupters.

One object of my invention is to provide 5 a circuit interrupter that shall be automatically opened upon the occurrence of a short-circuit on a circuit to be protected thereby, and that shall be reclosed when the short circuit is cleared or removed to render 10 the protected circuit normal.

Another object of my invention is to provide a circuit interrupter for a system, of the above indicated character, that shall be reclosed when the short-circuit conditions are 15 cleared and when the effective connected load is at or below a predetermined value.

A further object of my invention is to provide an interrupter, of the above-indicated character, that shall be simple and 20 economical in its construction and reliable in its operation.

In systems heretofore employed for controlling trolley-feeder conductors, large resistors having large current-carrying capacity 25 have been required. In such systems, upon the occurrence of an extremely heavy overload or short-circuit, the interrupter was opened to permit the insertion of a resistor or resistors of relatively low resistance and 30 having a relatively large current-carrying capacity to limit the current that might traverse the feeder conductor to a safe value. When the resistors were traversed by such current for a predetermined interval of time 35 and heated to a predetermined unsafe temperature, the feeder circuit was entirely disconnected from the source of energy until the fault might be cleared and the resistors cooled.

40 In the prior art, circuit breaker systems have been provided which insert a limiting resistor in series with a controlling winding when the circuit interrupter is opened. The current to the load circuit and fault traverse 45 the resistor and the control winding and maintain an auxiliary reclosing circuit open, until the current traversing the resistor diminishes to a predetermined value. The control winding is then deenergized to a sufficient degree to permit the auxiliary reclosing circuit to be reestablished and the interrupter reclosed.

50 Since the winding in such cases is trav-

ersed by the load and circuit current under abnormal conditions, it had to be made of 55 large conductor of low resistance, and could not be made as sensitive as a potential winding which can be made of a small conductor of high resistance.

By inserting the resistor directly in the 60 circuit when the interrupter is opened and utilizing the potential thereacross, which can be measured by a sensitive voltage coil, a greater sensitivity may be obtained to control the reclosing of the interrupter.

65 In practicing my invention, I provide means that are energized only upon the occurrence of a short-circuit upon the feeder circuit to open the interrupter to permit the effective insertion of a resistor of relatively 70 high resistance between the source of energy and the feeder-conductor circuit. Upon the clearance of the short-circuit and upon the increase of the effective-load resistance to or above a predetermined value, the interrupter is reclosed to shunt the limiting resistor. Since the opening of the interrupter 75 may be effected only by such currents as might result from short-circuit conditions, the interrupter, when reclosed to connect a 80 load of relatively low resistance to the main circuit, is not immediately reopened because of the sudden rush of current.

85 Figure 1 of the accompanying drawings is a diagrammatic view of an electrical circuit including an interrupter and a control system embodying my invention; and

90 Fig. 2 is a diagrammatic view of a similar circuit including a modified controlling device.

95 Referring to Fig. 1, a source 1 of direct-current electromotive force provides energy for a supply circuit 2 from which energy is supplied to a feeder circuit 3 through a circuit interrupter 4.

The interrupter 4 comprises a main switch 5, an auxiliary switch 6 and an operating coil 7 that serves to close both switches, when energized. The circuit of the coil 7 is completed through a switch 8 of a relay 9 and a switch 10 of a relay 11.

100 The relay 9 comprises the switch 8 and an operating coil 12. The relay 11 comprises the switch 10, a floating lever arm 13 and two controlling coils 14 and 15, respectively, 105 that control the switch 10 through the lever

arm 13. The circuit of the operating coil 12 of the relay 9 includes the switch 10 and a resistor 16.

5 A current transformer 17 and two relays 18 and 19, respectively, are employed to effect the actuation of the interrupter 4 to open the main switch 5 upon the occurrence of a short-circuit on the feeder circuit 3. The relay 18 comprises a switch 20 and an 10 actuating coil 21. The relay 19 comprises a switch 22 and an actuating coil 23.

Upon the occurrence of a short-circuit 15 that serves to effect the opening of the interrupter 4, a resistor 24, that is connected across the terminals of the switch 5, is inserted between the supply circuit 2 and the feeder circuit 3 to limit the current that may 20 traverse the latter circuit. The actuating coil 14 of the relay 11 is connected across the terminals of the resistor 24.

While conditions are normal in the system, the operating coil 12 of the relay 9 is energized to close the switch 8. Similarly, the coil 15 of the relay 11 is energized to 25 effect the closing of the switch 10. The circuit of the operating coil 7 of the interrupter 4 is thus completed to connect the coil 7 across the supply circuit 2. The interrupter 4 is thereby actuated to close the main 30 switch 5 and the auxiliary switch 6.

Upon the occurrence of a short-circuit on the circuit 3, as at the point A, the quick rate of change of current that traverses the circuit 3, and consequently, the primary 35 winding of the current transformer 17 suffices to quickly energize the winding of the relay 21 to effect the closing of the switch 20. Upon the closing of the switch 20, a circuit is completed through the auxiliary switch 40 6, the switch 20 and the coil 23 of the relay 19 that permits the energization of that coil to close the switch 22. The switch 22, when closed, completes a holding circuit for the coil 23 through the auxiliary switch 6 until 45 the interrupter 4 opens.

The moving members of the relays 18 and 50 19 are relatively light in weight and relatively sensitive. The switch 20, when momentarily closed, short-circuits the operating coil 12 of the relay 9. The immediate closing of the switch 22 thereupon serves to maintain the short-circuit about the coil 12 of the relay 9, and the switch 8 is permitted to open.

55 Upon the opening of the switch 8 of the relay 9, the interrupter 4 is also permitted to open, and the main switch 5 and the auxiliary switch 6 are opened. The opening of the auxiliary switch 6 de-energizes the coil 23 of the relay 19 to permit the switch 22 to open.

Upon the opening of the switch 5, the resistor 24, which, for example, may have a resistance of 60 ohms, is inserted into the 60 feeder circuit to limit the current that may

traverse the same to a maximum of 10 amperes, assuming that the voltage of the circuit 2 is normally 600 volts. When the short-circuit conditions in the feeder circuit 3 are cleared and the effective load resistance connected thereto equals or exceeds 0.6 of an ohm, the maximum current that may traverse the interrupter is 9.9 amperes.

Assuming short-circuit conditions on the circuit 3, the full voltage of the circuit 2, 75 normally 600 volts, will be consumed in the resistor 24 and, consequently, the corresponding potential difference thereacross will be effective in energizing the coil 14 of the relay 11. Since the winding 15 is correspondingly energized by a potential difference of 600 volts, the relay 11 is maintained in a balanced position at which position the switch 10 is maintained open.

However, when the short-circuit is cleared 80 and the resistance of the connecting load increases to or above 0.6 of an ohm, the potential difference across the terminals of the resistor 24 is 594 volts. The difference between the potentials applied to the two 85 coils 14 and 15 is thus 6 volts. Since the relay 11 may be arranged to obtain a sensitivity of 1%, the difference in the degree of energization between the two coils 14 and 15, effected by the difference of 6 volts, will 90 suffice to effect the closing of the switch 10.

The closing of the switch 10 immediately completes the circuit of the operating coil 12 of the relay 9, whereupon the switch 8 is closed. The closing of the switch 8 completes the circuit of the operating coil 7 of the interrupter 4, and the main switch 5 is 95 thereupon reclosed.

When the switch 5 is closed and the resistance of the connected load is 0.6 of an ohm, 100 1000 amperes will immediately traverse the circuit. However, since this value of current is far below such value as might be caused to traverse the circuit by short-circuit conditions, the current transformer 17 105 is not sufficiently energized to effect the actuation of the relays 18 and 19.

If, however, the magnetic circuit of the current transformer 17 should not be magnetized, the sudden rush of current of such 110 value might be sufficient to actuate the relays 18 and 19 to effect the opening of the main interrupter. Upon the occurrence of such opening, however, the magnetic circuit would be so magnetized and relatively so 115 saturated that the consequent rush of current upon the next reclosing would not again be sufficient to effect the operation of the relays 18 and 19.

The feeder circuit 3 may be connected directly, through a series of sections connected 120 by sectionalizing switches, to a distant source of energy, but the opening of the interrupter 4, upon the occurrence of short-circuit, and the reclosing, upon the clearance of the 125 130

short-circuit, at a predetermined value of load resistance, will be effected irrespective of whether potential is applied to the circuit 3 from an exterior source.

5 The operation of the system illustrated in Fig. 2 is similar to that described in connection with the system illustrated in Fig. 1 with the exception of the relay 25 which comprises a switch 26, an energizing coil 10 27 and a spring 28 provided with an adjusting device 29. Upon the opening of the main switch 5 of the interrupter 4, an auxiliary switch 30 is closed that serves to connect the winding 27 of the relay 25 across 15 the terminals of the limiting resistor 24.

While the value of the potential across the terminal of the register 24 is 594 volts or more, the coil 27 is sufficiently energized to maintain the switch open. When the potential difference across the terminals of the 20 resistor decreases to a value below 594 volts by reason of an increase of the load resistance to a value exceeding 0.6 of an ohm, the spring 28 serves to close the switch 26 25 against the force of the winding 27.

The interrupter and the control system embodied in my invention, as illustrated in the accompanying drawings, will thus disconnect a load circuit from a supply circuit 30 upon the occurrence of short-circuit conditions in the load circuit and will immediately reconnect the load circuit when the short-circuit conditions are cleared and the connecting load of the load circuit is at or 35 above a predetermined value.

40 My invention is not limited to the specific devices illustrated or to the specific arrangement of those devices, since modifications may be made therein within the spirit and scope of the invention, as set forth in the appended claims.

I claim as my invention:—

45 1. An automatically reclosing circuit-interrupting device comprising means for connecting two circuit conductors, an operating coil therefor, a switch in circuit with the coil, and means for controlling the switch comprising a resistor connected directly across the terminals of the interrupting device and means responsive to the potential difference thereacross when the switch is open.

50 2. An automatically reclosing circuit-interrupting device comprising means for connecting two circuit conductors, and operating coil therefor, a switch in circuit with the coil, and means for controlling the switch comprising a resistor connected directly across the terminals of the interrupting device, means responsive to the potential

difference thereacross when the switch is open and means for controlling the effectiveness of such potential difference.

3. In an electric system, the combination with a supply circuit, a load circuit and a 65 circuit interrupter therebetween, of a current-limiting resistor connected in parallel relation to the circuit interrupter, means for opening the circuit interrupter in response to predetermined abnormal conditions in the 70 load circuit, and means for reclosing the circuit interrupter when the resistance of the load circuit equals or exceeds a predetermined value, comprising a closing coil for the circuit interrupter, a switch for controlling the energization of the closing coil, 75 and two opposed coils for controlling the operation of the switch, one of said coils being connected in parallel relation to the supply circuit and the other of said coils being connected in parallel relation to the current-limiting resistor.

4. In an electric system, the combination with a supply circuit, a load circuit and a circuit-interrupter therebetween, of a current-limiting resistor connected in parallel relation to the circuit-interrupter, means for opening the circuit interrupter in response to predetermined abnormal conditions in the 80 load circuit, and means for reclosing the circuit interrupter when the resistance of the load circuit equals or exceeds a predetermined value, comprising a closing coil for the circuit-interrupter, a switch for controlling the energization of the closing coil, 85 and two coils for controlling the operation of the switch, one of said coils being so disposed as to be responsive to the potential across the supply circuit and to tend to close the switch, and the other of said coils being so disposed as to be responsive to the potential across the current-limiting resistor and to tend to open the switch.

5. In an electric system, the combination with a supply circuit, a load circuit and an interrupter therebetween, of means for opening the interrupter upon the occurrence of abnormal conditions in the load circuit, a resistor connected directly across the terminals of the interrupter for conducting a 100 current of limited value to the load circuit after the opening of the interrupter and means responsive to the drop of potential across the resistor for controlling the reclosing of the interrupter.

105 In testimony whereof, I have hereunto subscribed my name this 18th day of April, 1921.

CHARLES A. BUTCHER.
